UNITED STATES PATENT OFFICE.

DANA OSGOOD, OF HOPEDALE, MASSACHUSETTS, ASSIGNOR TO DRAPER CORPORATION,
OF HOPEDALE, MASSACHUSETTS, A CORPORATION OF MAINE.

SHUTTLE FOR SIDE-MOTION FEELER-LOOMS.

1,303,583.

Specification of Letters Patent. Patented May 13, 1919.

Application filed September 7, 1918. Serial No. 253,030.

To all whom it may concern:

Be it known that I, DANA Osgood, a citizen of the United States, residing at Hopedale, county of Worcester, State of Massachusetts, have invented an Improvement in 5 Shuttles for Side-Motion Feeler-Looms, of which the following description, in connection with the accompanying drawing, is a specification, like characters on the drawing 10 representing like parts.

This invention relates to the construction of shuttles for use in side motion feeler looms. In such type of looms, as is well known to those skilled in the art, a feeler is 15 employed which upon the beat up of the lay enters the shuttle recess and contacts with the mass of filling upon the filling carrier. The feeler mechanism is so constructed that, when the running filling has reached a pre- 20 determined degree of exhaustion or has become entirely exhausted, the feeler has a side motion, usually due to it, or some portion of it, slipping on the smooth surface of the filling carrier, and this side motion is 25 utilized to effect the initiation of filling replenishment or other change in the operation of the loom.

The object of this invention is to provide 30 a shuttle having means for preventing a premature side motion of the feeler taking place and consequently a premature replenishment of the shuttle with a fresh filling carrier or other premature change in the operation of the loom.

The danger of such premature action, 35 which this invention prevents, arises chiefly from the not infrequent mis-positioning of the shuttle longitudinally at the time the feeling action occurs. This mis-positioning 40 of the shuttle is due to a slight rebound or a failure fully to enter the shuttle box at the feeling end of the loom and in either case results in bringing the path of feeler movement nearer the butt end of the shuttle 45 recess than the normal path of feeler movement. This brings the feeler opposite the smooth outer wall of the shuttle and consequently, when the beat up occurs, the feeler engages a smooth surface and side motion 50 takes place in the same manner as if it had engaged a depleted bobbin barrel.

In the application of Thomas F. Brazeil, 55 Serial No. 254,230 filed September 16, 1918, the broad invention for securing the desired object is disclosed and is shown in its pre-

ferred form embodied in a shuttle in which the usual feeler slot in the shuttle wall is extended toward the butt end of the shuttle recess so as to expose the means, such as the usual metal clamping guide, for holding the 60 butt of the filling carrier, and in which the surface thus exposed is provided with serrations sufficient to prevent side motion of the feeler when the feeler is in contact therewith.

65

The present invention, which is subsidiary to the aforesaid broad invention, eliminates any extension of the feeler slot beyond that required for the normal feeling action and provides the shuttle with the required serrated surface on its outer wall adjacent, and longitudinally in line with, that end of the slot nearer the butt end of the shuttle recess; and preferably this serrated surface is formed in the material of the shuttle body 70 itself. Thus an extremely simple and efficient construction for effecting the desired result is secured.

75

The nature and object of the invention will appear more fully from the accompanying 80 description and drawing and will be particularly pointed out in the appended claims.

85

In the drawings which represent the preferred form of the invention,

Figure 1 is a side elevation of the end of a shuttle;

85

Fig. 2 is a top plan view of the shuttle with the butt and a portion of the barrel of a filling carrier indicated in dotted lines;

90

Fig. 3 is a view in cross section taken on the line A—A, in Fig. 1.

95

From the statement already made it will be apparent that the construction and operation of the loom and of a side motion feeler mechanism is unchanged by this invention which has to do only with the construction of the shuttle itself. Consequently this description is restricted to the shuttle.

100

In its general construction the shuttle may be of any usual type. In the preferred form illustrated the body of the shuttle is provided with the usual recess 1 extending through the shuttle from top to bottom to receive the filling carrier which, as indicated 105 in dotted lines, may be a wooden bobbin 2 of usual type. Such a filling carrier is commonly clamped and held in the shuttle recess 1 by a bifurcated metal clamping guide of usual construction. The shank 3 of this 110

- clamping guide is rigidly secured in the body of the shuttle with the arms 4 and 5 projecting into the recess 1 substantially parallel to the side walls 6 and 7 thereof.
- 5 The inner surfaces of these arms are usually grooved at 8 to coöperate with rings 9 on the butt of the filling carrier in accurately positioning and firmly holding the filling carrier.
- 10 The side wall 7 is slotted longitudinally at 10 opposite the axis of the filling carrier to enable the feeler to enter the recess 1 and feel the filling on the filling carrier. In the case of a side motion feeler mechanism, with
- 15 which the shuttle of this invention is to coöperate, the feeler entering the slot 10 upon the beat up contacts with the filling carrier; if the required amount of filling is present side motion of the feeler is absent,
- 20 but, if the filling has became exhausted or has reached a predetermined degree of exhaustion, then the feeler contacting with the relatively smooth and hard surface of the filling carrier undergoes some sort of side
- 25 motion depending upon the character of the specific feeler mechanism employed and this side motion is utilized through a suitable train of mechanism to initiate filling replenishment or other change in the operation of
- 30 the loom.
- But, as already pointed out, longitudinal mis-positioning of the shuttle at the time of feeling, due to rebound or improper boxing of the shuttle or other cause, will so relate
- 35 the shuttle to the path of feeler movement that the feeler will not be opposite the filling on the filling carrier but will be in a position opposite a point nearer the butt of the filling carrier or the butt end of the shuttle recess.
- 40 Under such conditions, when the beat up occurs, the feeler contacts with a smooth hard surface which has no relation to the condition of the filling on the filling carrier and consequently side motion may take place resulting in premature initiating action of the
- 45 feeler mechanism.

This result is obviated in the present in-

vention by providing a serrated surface on the outer wall of the shuttle adjacent, and longitudinally in line with, that end of the slot 10 nearer the butt end of the shuttle recess. This serrated surface is preferably presented by forming vertical ridges and grooves 11 in the material of the shuttle body which is usually composed of wood but any suitable means for presenting the serrated surface in the specified location may be employed. So also the term "serrated" is to be taken to include any form of roughness sufficient to prevent side motion of a feeler in contact therewith.

Thus it will be seen that a simple and efficient construction is provided which prevents premature side motion of the feeler with its consequent premature initiation of filling replenishment or other change in the operation of the loom when feeling takes place with the shuttle longitudinally mis-positioned.

Having fully described my invention, what I claim as new and desire to secure by Letters Patent is:

1. A shuttle for use in side motion feeler looms provided with a filling carrier recess and with means to clamp and hold a filling carrier by its butt in said recess, one wall of said recess being slotted to permit the passage of the feeler therethrough, the said shuttle being further provided on its outer wall with a serrated surface adjacent, and longitudinally in line with, that end of the slot nearer the butt end of the shuttle recess whereby, if the shuttle be longitudinally mispositioned at the time of feeling, the feeler contacting with said serrated surface will be prevented thereby from premature side motion.

2. A shuttle for use in side motion feeler looms having the construction defined in claim 1 in which the said serrated surface is formed in the material of the shuttle body.

In testimony whereof, I have signed my name to this specification.

DANA OSGOOD.
